ROTARY VALVE FOR INTERNAL
COMBUSTION ENGINESCharles W. Hall, Denver, Colo., assignor to
Malcolm S. Losey, Denver, Colo.Application October 10, 1929, Serial No. 398,598
Renewed January 20, 1933

4 Claims. (Cl. 123—190)

This invention relates to rotary valve construction for internal combustion engines and has for its principal object the provision of a simple and efficient rotary valve which will be positive and quick acting, efficiently cooled and gas tight.

Another object of the invention is to provide a rotary valve in which the valves for any desired number of cylinders are secured to a single common operating shaft which will be supported at a plurality of intervals so that warping, cramping, etc. are avoided and so that the valves themselves will have no contacting or wearing surfaces.

A further object of the invention is to provide means for effectively sealing the ports of a rotary valve to prevent the escape of gases from one port to another.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a plan view of an internal combustion engine partially broken away to illustrate the rotary valve construction.

Fig. 2 is a side elevation of the sealing plate and ring employed for sealing the cylinder port to the rotary valve.

Fig. 3 is a plan view of the sealing plate.

Fig. 4 is an enlarged vertical section taken on the line 4—4, Fig. 1.

Fig. 5 is a similar section illustrating an alternate arrangement of rotary valve passages. This section is taken on the line 5—5, Fig. 6.

Fig. 6 is a longitudinal section through the form of Fig. 5, taken on the line 6—6, in that Figure.

Fig. 7 is a detail view of an alternate form of sealing plate.

Construction

In the drawings a four cylinder engine block is illustrated at 10. The block may be provided with any desired number or aligned cylinders. A cylinder head 11 extends throughout the length of the engine block 10 and closes the upper extremities of all of the cylinders. Hol- low, cylindrical rotary valves 12 are seated in

semi-cylindrical depressions in the top of the cylinder head 11, one valve being placed over each of the cylinders and covered by means of a cap 13. The cap 13 contains semi-spherical depressions which fit snugly over the rotary valves 12 at each of the cylinders.

The cylinder head 11 and the cap 13 are clamped together and to the engine block 10 by means of bolts 14 and clamp nuts 15. The cylinder head 11 is provided with a suitable spark plug socket 16 and a cylinder passage 17 for each of the cylinders. The cylinder passages 17 extend directly upward over the center of each cylinder.

The upper extremity of each cylinder passage 17 is surrounded by a sealing collar 18 having a cylindrical concavity in its upper face to fit against the rotary valve 12. The lower face of the sealing collar 18 is surrounded by an expandable sealing ring 19 provided with a series of slots 29, as illustrated in Fig. 2. The slots 29 are arranged in staggered relation so that the divisions between the slots of one series may be depressed into the spaces provided by the slots of the other series. This allows the ring to be compressed in an axial direction so that it will constantly act to force the sealing collar 18 against the rotary valve 12.

All of the rotary valves 12 are secured on a common valve shaft 20 which extends throughout the length of the engine block and is supported in a series of ball bearings 21. The races of the bearings 21 are clamped between the cylinder head 11 and the cap 13 and are positioned between each rotary valve 12 and at the extremities of the engine block as illustrated in Fig. 1. The entire weight of the valves 12 and the pressures against the valves are absorbed by the bearings 21, so that the surface of the valves will not be exposed to wear. The shaft 20 is driven in any desired manner from the engine such as through the medium of a silent chain 22.

Both the cylinder head block 11 and the valve cap 13 are hollow so that water jacket spaces 23 surround the concavities for the rotary valves and all of the passages leading thereto. This efficiently cools the valves so that they may be properly lubricated and so that they will not be expanded or warped.

Within the valve cap 13, a separate intake passage 24 communicates between each valve 12 and an intake manifold 25, within the head 11 a separate exhaust passage 26 communicates between each valve 12 and an exhaust manifold 27.

110

In each rotary valve 12 an exhaust chamber 28 is provided which registers at its extremities with the passage 17 to the cylinder and the exhaust passage 26 as the valve 12 rotates. It will be noted that the exhaust passage 26 is placed to one side of the passage 17 so that the exhaust chamber 28 can only register with the intended passages.

The entire center of the rotary valve is hollow to form an intake chamber 31, which completely surrounds the exhaust chamber 28. Open partitions 30 are formed in the intake chamber to stiffen the wall of the valve 12. The intake chamber 31 is provided with an intake port 32 which registers with the intake passage 24 and with a cylinder port 33 which registers with the cylinder passage 17. It will be also noted that the ports 32 and 33 are staggered or placed to one side of each other so that they can only register with their intended passages.

Operation

When the engine is started the intake port 32 will register with the intake passage 24 allowing gas to be drawn from the intake manifold 25 through the intake chamber 31, the port 33, and the passage 17 to the cylinder. The ports 32 and 33 will now move out of alignment with the respective passages 24 and 17 allowing the charge to be compressed within the cylinder and exploded therein. The exhaust chamber 28 will now align with the cylinder passage 17 and the exhaust passage 26, so as to allow the combustion gases to flow from the cylinder through the passage 17, to the manifold 27. This cycle of operations will be constantly repeated during the operation of the engine.

It will be noted that the exhaust for a portion of its travel will be completely surrounded by intake gases. This has a double advantage, first, it cools the exhaust and second, it heats the intake gases thereby increasing their combustion efficiency. In cooling the exhaust it prevents undue heating of the rotary valve so that warping and "freezing" are avoided.

Alternate form

An alternate form of the invention is illustrated in Figs. 5, 6, and 7, the operation of which is similar to the previously described form. In this form, however, a slightly different arrangement of passages in the rotary valves is employed and a sealing sleeve is provided about the rotary valve in addition to the sealing collar previously described.

In this form the top of the cylinder block 10 is closed by a head block 35 which is in turn covered by a valve cap 36. The rotary valves, illustrated at 37, rotate between the head block 35 and the cap 36, as in the previous form. Each alternate pair of cylinders is provided, in the head block 35, with a discharge passage 50 and each cylinder is provided with a cylinder passage 38. The cap 36 provides a separate intake passage 44 for each cylinder. The discharge passage 37 branches at its inner extremity and terminates in two exhaust ports 39.

Within the rotary valve an exhaust chamber 40 is formed which, at one position of the valve, bridges across between the cylinder passage 38 and one of the exhaust ports 39 as illustrated in Fig. 6.

The remainder of the hollow interior of the valve 37 forms an intake chamber 41. The intake chamber 41 contains a cylinder port 42 and

an intake port 43, which register with the cylinder passage 38 and the intake passage 44, respectively.

The operation of the alternate form is exactly similar to that of the previously described form. The molding of the rotary valves, however, is somewhat simplified in that the exhaust chamber extends parallel to the supporting shaft 20, and the head block 35 is simplified in that a single exhaust passage 37 serves for two cylinders.

In connection with the alternate form a sealing sleeve 34 is illustrated. This sleeve could also be incorporated in the preferred form, if desired.

The sealing sleeve 34 comprises a resilient metallic sleeve having a longitudinal expansion split 45. Formed upon the sleeve 45 is a collar 46 arranged to extend downwardly into the cylinder passage similarly to the sealing plate 18. The sleeve 46 may be provided with a sealing ring 47 similar to the sealing ring 19, if desired. The sleeve is provided with ports to align with and maintain the intake passage 44 and the discharge port 39 open.

Normally the sleeve 34 has a diameter slightly less than the diameter of the rotary valve 37 so that when in place it will snugly engage the valve and close all of the ports therein, when not in alignment with one of the passages 37, 38 or 44, thus effectively sealing the escape of gas from one port to another.

Of course, the common exhaust passage 37 necessitates an opposite arrangement of ports for adjacent rotary valves as illustrated in Fig. 110 6, so as to bring the exhaust ports 39 together in a common exhaust passage 37.

It is desired to call attention to the oiling system of this engine. Oil is pumped from the rear of the engine through an oil passage 48 in the shaft 20. This oil feeds through ports 49 to the various ball bearings 21 and discharges at the forward extremity of the shaft to flow over the drive chain and gears 22.

The partitions 30 within the intake chamber 120 serve as vanes to beat and intimately mix the intake gases and also serve on the order of a centrifugal pump as a supercharger to discharge these gases under pressure to the cylinder.

While a specific form of the invention has been described and illustrated herein it is desired to be understood that the same may be varied, within the scope of the appended claims without departing from the spirit of the invention.

Having thus described the invention, what I claim and desire secured by Letters Patent is:—

1. In an internal combustion engine having a cylinder passage extending vertically from the cylinder; a hollow cylindrical valve arranged to rotate on a horizontal axis above said cylinder passage; an intake passage; an exhaust passage; said intake and exhaust passages opening to said rotary valve substantially at right angles to and on each side of said cylinder passage; two ports in said rotary valve adapted to align with said cylinder passage at predetermined times; a third port in said valve adapted to align with said intake passage; a fourth port in said valve adapted to align with said exhaust passage; a conduit within said valve connecting one of said first ports with said fourth port, the remainder of the hollow interior of said valve being open to the other of said first ports and said third port.

2. In an internal combustion engine having a cylinder passage extending vertically from the cylinder; a hollow cylindrical valve arranged to rotate on a horizontal axis above said cylinder passage; an intake passage; an exhaust passage; said intake and exhaust passages opening to said rotary valve substantially at right angles to and on each side of said cylinder passage; two ports in said rotary valve adapted to align 10 with said cylinder passage at predetermined times; a third port in said valve adapted to align with said intake passage; a fourth port in said valve adapted to align with said exhaust passages; a conduit within said valve connecting one of said first ports with said fourth port, the remainder of the hollow interior of said valve being open to the other of said first ports and said third port. 80
3. In an internal combustion engine having a cylinder passage extending vertically from the cylinder; a hollow cylindrical valve arranged to rotate on a horizontal axis above said cylinder passage; an intake passage; an exhaust passage; two ports in said rotary valve adapted to align 15 with said cylinder passage at predetermined times; a third port in said valve adapted to align with said intake passage; a fourth port in said valve adapted to align with said exhaust passages; a conduit within said valve connecting one of said first ports with said fourth port, the remainder of the hollow interior of said valve being open to the other of said first ports and said third port, said intake passage being arranged at a higher elevation than said exhaust 20 passage so that the intake gases must cross substantially the entire interior of said valve before reaching said cylinder port so as to cool the former. 90
4. In an internal combustion engine having a cylinder passage extending vertically from the cylinder; a hollow cylindrical valve arranged to rotate on a horizontal axis above said cylinder passage; an intake passage; an exhaust passage; said intake and exhaust being in a different plane and on each side of said cylinder passage; two ports in said rotary valve adapted 25 to align with said cylinder passage at predetermined times; a third port in said valve adapted to align with said intake passage; a fourth port in said valve adapted to align with said exhaust passages; a conduit within said valve connecting one of said first ports with said fourth port, the remainder of the hollow interior of said valve being open to the other of said first ports and said third port, said intake passage being arranged at a higher elevation than said exhaust 30 passage so that the intake gases must cross substantially the entire interior of said valve before reaching said cylinder port so as to cool the former. 95
5. In an internal combustion engine having a cylinder passage extending vertically from the cylinder; a hollow cylindrical valve arranged to rotate on a horizontal axis above said cylinder passage; an intake passage; an exhaust passage; said intake and exhaust being in a different plane and on each side of said cylinder passage; two ports in said rotary valve adapted 35 to align with said cylinder passage at predetermined times; a third port in said valve adapted to align with said intake passage; a fourth port in said valve adapted to align with said exhaust passages; a conduit within said valve connecting one of said first ports with said fourth port, the remainder of the hollow interior of said valve being open to the other of said first ports and said third port, said intake passage being arranged at a higher elevation than said exhaust 40 passage so that the intake gases must cross substantially the entire interior of said valve before reaching said cylinder port so as to cool the former. 100
